UNITED STATES PATENT OFFICE.

CHARLES CROMPTON, OF WORCESTER, MASSACHUSETTS.

STEAM-GENERATOR.

SPECIFICATION forming part of Letters Patent No. 738,664, dated September 8, 1903.

Application filed February 12, 1902. Serial No. 93,680. (No model.)

To all whom it may concern:

Be it known that I, CHARLES CROMPTON, a citizen of the United States, residing at Worcester, in the county of Worcester and State of Massachusetts, have invented an Improvement in Steam-Generators, of which the following description, in connection with the accompanying drawings, is a specification, like letters on the drawings representing like parts.

This invention relates to steam-generators such as are adapted for use in connection with motor-vehicles which use steam as the motive power; and the object of the invention is to provide a novel form of boiler mechanism wherein a large amount of heating-surface is provided, so that the steam may be generated rapidly.

In constructing my steam-generator I prefer to use what I term a "battery" of boilers, the said battery comprising a plurality of independent boilers which are connected to each other both above and below the water-line, whereby the water-level in all of the boilers remains the same, and the same feed-pump mechanism will operate to feed water to all of the boilers of the series. The boilers are so constructed that should any one boiler become damaged the communication between the said boiler and the remaining boilers is shut off, thereby cutting the said boiler out of the series without in any way affecting the operation of the remaining boilers. Any suitable means may be employed for furnishing heat to the boilers, and for convenience I have illustrated one form of burner adapted to burn gasolene and so constructed and connected with the engine that the exhaust-steam from the engine is delivered to the burner and is thereby partially or wholly consumed. This construction of boiler and heating device makes my invention especially applicable to motor-vehicles, for a large amount of heating-surface is obtained and the exhaust-steam is substantially destroyed by passing the same through the burner, with the result that any annoyance which comes from the escaping steam in the common form of steam-driven vehicles is entirely avoided.

Referring to the drawings, Figure 1 is a vertical section through the rear portion of the body of a motor-vehicle having my improved

boiler or steam-generator applied thereto. Fig. 2 is a top plan view of the steam-generator. Fig. 3 is a transverse section substantially on the line $x x$, Fig. 2. Fig. 4 is an enlarged vertical section of one of the boilers. Fig. 5 is a detail showing the lay-out of the water-pipes connecting the boilers, and Fig. 6 is a detail of the smoke-flue.

Although I have herein described my invention as it will preferably be constructed when applied to a steam-driven motor-vehicle, yet I wish it understood that my invention is not limited to motor-vehicles, but may be used in steam-yachts or in any other place where a steam-generator is required.

My steam-generator comprises a series of boilers which are connected together to form what I have termed a "battery" of boilers, and said boilers are so connected that the steam generated in each boiler passes to a common steam-drum, the connection being such that the water-level in all the boilers will remain the same. Preferably when applied to a steam-driven motor-vehicle I use two such batteries of boilers, as shown in Fig. 2, the said boilers being supported in the rear portion of the body of the vehicle and having between them the steam-engine a , which may be of any suitable type, the said steam-engine being connected by any suitable or usual gearing with the driven axle of the vehicle. The steam-engine I have herein chosen to illustrate is the same as that described and claimed in my copending application, Serial No. 76,549, filed September 25, 1901, and the driving-gear for connecting the engine with the driven axle of the vehicle will be the same as that illustrated in my co-pending application, Serial No. 76,548, filed September 25, 1901. Further description of the engine and driving mechanism therefore is unnecessary in this application.

The individual boilers each comprise a boiler-shell 3 of suitable material, such as steel plate, and which is shown in Fig. 1 as cup-shaped, it having the outwardly-turned flange 4 at the upper end thereof, which is secured to the plate 5 in any suitable way, as by rivets. The plate 5, which I will herein-after term the "boiler-plate," thus forms the top or head of each of the boilers in either battery, (see Fig. 1,) and the said plate, with

the boilers attached, is secured in position in any suitable way, as by bolting the same at its ends to the channel-iron cross-pieces 6, which extend across the body of the vehicle, 5 as shown in Fig. 1, and at its sides to the side pieces 14 of the vehicle by means of suitable angle-irons 15. (See Fig. 3.)

I will preferably copper-plate each individual boiler 3 both inside and outside, such 10 copper-plating filling up any cracks which may exist and rendering the boiler non-corrosive.

It is understood that there is one boiler-plate 5 for each battery of boilers, and secured to the boiler-plate and surrounding 15 each battery is a suitable wall 7, forming a casing which incloses the boilers of the battery, the said casing having in its lower portion any suitable burner for heating the water in the boilers. It will thus be seen that 20 the plate 5 forms a partition which extends across the casing and that the compartment beneath the partition constitutes a combustion-chamber. The walls of the casing preferably will be made of any suitable non- 25 combustible material, and, as shown in Figs. 1 and 4, they comprise inner and outer metallic walls having a filling of asbestos or other heat-resisting material. The lower portion of the casing will be provided on the 30 sides and back with the shoulders 8, which are adapted to rest upon the framing 9 of the vehicle-frame to thus support the casing in proper position.

Each boiler has a series of flues or boiler-tubes 10 passing through the same, the said tubes being connected in any suitable way at the lower end in the bottom 11 of the boiler and being fastened at their upper end in the boiler-plate 5, as plainly seen in Fig. 4.

40 By using a series of independent boilers secured to a boiler-plate 5 in such a way as to leave a space between the separate boilers it will be seen that the heating-surface which is provided is the entire heating-surface of 45 the flues 10 of the boilers and also the entire outer-surface of each boiler, for the heat from the burner beneath the boilers will pass upwardly around all the boilers and upon striking the plate 5 will be deflected downward 50 and thence upward through the flues 10.

Above each battery of boilers is a smoke-chamber 12, said chamber being formed by the boiler-plate 5 and the top plate 17, of any suitable material, which forms the top of the 55 body of the vehicle and which is bolted at its front and rear ends to the upper sides of the channel-irons 6, as seen in Fig. 1. The top plates 17 will preferably each have a lining 18 of a suitable non-heat-conducting material, such as asbestos, to prevent the plate 17 from becoming too hot, and between the plates 17 is the engine-plate 23, which is secured at its front and rear ends to the channel-iron 6 and to which the supporting-plate 60 24 of the engine is bolted, as described in my copending application, Serial No. 76,548, filed 65 September 25, 1901. The plate 23 is support-

ed centrally of its length by studs 25, connecting the same and the boiler-plates 5. The inner walls of the casings which surround each battery of boilers are extended upwardly above the plate 5, as shown at 18', Fig. 3, and are connected in any suitable way with the engine-plate 23, thus forming, with the upper plate 17 and the boiler-plate 5, the 75 smoke-chamber 12, above described, into which the products of combustion pass from the boiler-tubes 10, the said smoke-chamber having the smoke-flues 13, through which the said products of combustion escape to the air. 80 The smoke-chambers 12 above each battery of boilers are independent from each other and each have a smoke-flue 13. With this construction the casings 7 are each divided by the plate or partition 5 into two compartments, one of which (that beneath the partition) constitutes the combustion-chamber and has the boilers included therewith and the other (that above the partition) constitutes a smoke-chamber, into which the flues 90 from each of the boilers open.

Fig. 6 illustrates in detail the construction of the smoke-flue, it comprising the stem having the hollow head portion 19, provided at each end with a hood 21, said hood being connected to the head 19 by suitable arms, so as to leave a passage between the same and the head for the escape of the products of combustion. This construction of hood is especially advantageous, for it allows for a perfect draft regardless of the direction of movement of the vehicle, and the hood portions 21 prevent a back draft.

Referring to Figs. 1, 2, and 3, it will be seen that each boiler is connected at its upper end 105 or above the water-line by means of steam-pipes with a common steam-pipe 26, which is in the nature of a steam-drum, and the two steam-drums 26 are connected by a valved connection 27, one of said steam-pipes being 110 connected by a pipe 28 with the valve-chest of the steam-engine. The lower end of each boiler is connected to a system of connected water-pipes, so that the water in the various individual boilers has the same level, and 115 said connected system of water-pipes is preferably connected to a suitable pump for supplying water to the boilers.

Fig. 5 shows the lay-out of the water-pipes underneath the boilers, and it will be seen 120 that there are a series of connected pipes 29 situated under each battery of boilers, said two series of pipes being connected together at one end, as at 30.

I have arranged my boilers of each battery 125 in parallel rows, as seen in Fig. 2, and a pipe 29 extends under each row of boilers, and each pipe 29 has the upwardly-projecting nipple 35, which projects into the boiler. The pipes 29 are connected in any suitable way 130 with any usual mechanism for supplying water to the boilers, one form of such mechanism being shown as a feed-pump 31, operated from the crank-shaft 32 of the engine and

communicating with the connection 30, the said pump taking water through the pipe 31 from the water-tank 34, which is preferably placed under the seat of the vehicle.

5 In the preferred embodiment of my invention the nipple 35 will be made in two sections, the upper section 36 being screwed into the lower section and having in its end a valve-seat 37, with which co-operates a suitable check-valve 38, shown in this embodiment of my invention as a ball-valve. Screwed upon the upper section 36 of the nipple is a perforated pipe 40, which extends upwardly through each boiler and is screwed at its upper end into the plate 5, the upper screw-threaded end of the pipe 40 being enlarged somewhat to form a suitable valve-seat 41 for the check-valve 42. The steam-pipes 43, which extend over each row of boilers and 15 which are connected to the steam-drum 26, have the depending nipples 44, which are coupled to the upper projecting ends of the pipe 40 by any suitable means, such as nuts 45. It will thus be seen that the water-pipes and 20 the steam-pipes are connected by perforated pipes which extend through each of the boilers, and a check-valve is employed at either end of said perforated pipe, which seats toward the boiler.

25 From the above description it will be seen that the weight of the check-valves 38 at the lower end of the perforated pipe will normally hold the same open, the said check-valves being supported by any suitable stops, such as pins 46, and that therefore each boiler has a normally open connection with the water-pipes and with the feed-pump, so that the water-level in all of the boilers will remain the same, and the feed-pump operates to supply water to each boiler, the water passing into the nipples and through the lower apertures in the pipe 40. The steam generated in each boiler passes through the upper perforations in the pipe 40 and thence into the 30 steam-pipes 43 and to the steam-drum 26. The check-valve 42, which is normally closed, is lifted by the steam-pressure and allows the steam to escape, suitable stops 46 serving to limit the play of said valve. In case 35 any one of the boilers should become damaged in any way, as if the boiler should burst or as if one of the boiler-flues should be blown out, the pressure in such boiler will of course suddenly decrease, and the check-valves 42 and 38 will instantly be seated and shut off communication between said boiler and the remaining boilers. Each individual boiler is comparatively small in size, and therefore even should any boiler explode comparatively 40 little damage would be done, for the mechanism described instantly cuts off the exploded boiler from the other boilers, which are in no way affected, and the engine can continue to be run.

45 As seen in Figs. 2 and 3, the water-pipe 30 is provided with a valve 30^a, whereby the supply of feed-water may be shut off from the

boilers of the battery at the left, Fig. 3, and the connection 27 is provided with a valve 27^a, by means of which construction both batteries of boilers or only one may be used, as circumstances require. When, therefore, only a small quantity of steam is required to propel the vehicle, the valves 27^a and 30^a may be closed, in which case the left-hand battery of 75 boilers in Fig. 3 would be cut out and the other battery only would be available in generating steam, while when it is necessary to utilize the full steaming capacity of the plant both of said valves will be open.

80 As seen in Fig. 2, the boiler-plate 5 is preferably provided with a plurality of small apertures 103 between the individual boilers, said apertures in the event of an explosion allowing some of the compressed gases which are in the spaces between the boilers to pass directly into the smoke-chamber, and thus relieving the lifting force on said plate. It is the intention of the invention that in the ordinary use of the boiler the hot gases which 90 pass in the spaces between the boilers will be deflected downward and will pass into the smoke-chamber through the flues 10.

85 Any suitable means may be employed for generating heat; but I have herein illustrated for convenience a burner similar in some respects to that illustrated in my copending application, Serial No. 76,547, filed September 25, 1901, and inasmuch as the burner forms no part of my present invention I will merely 95 briefly refer to the construction illustrated.

90 The lower part of each casing is illustrated as divided by the horizontal partitions 50, 51, and 52 into the combustion-chamber 53, in which the boilers are situated, the vapor-chamber 54, and the lower chamber 55, into which the exhaust-steam from the engine a is delivered through the pipe 56.

95 57 is a pipe which connects with any suitable source of gasolene or other hydrocarbon-supply and which opens into a valved chamber 58, said chamber having a suitable nozzle to direct the vaporized fuel into the pipe 59, from which it is delivered to the vapor-chamber 54.

100 Extending through the chambers 54 and 55 are a series of tubes 60, which are open at each end, the lower ends of each of the tubes having a series of apertures 61 opening into the exhaust-chamber 55. Surrounding the 105 upper end of each tube or flue 60 are a series of small apertures 64, through which the vaporized fuel passes into the combustion-chamber, and by reason of this construction not only is air drawn up through the flues 60 to 110 aid in combustion, but the exhaust-steam from the chamber 55 is also admitted to the flues and is thus burned with the gaseous fuel and rendered invisible.

115 Although I have herein illustrated but a few 120 of the flues 60, it will be understood that the entire space beneath the boilers is occupied by such flues.

125 70 designates any suitable regulator con-

trolling the valve in the chamber 58, said regulator being connected by a pipe 71 with the steam-drum, whereby the degree of opening in the valve in the chamber 58 is varied by the steam-pressure.

It will be understood that there is a burner beneath each battery of boilers and that the said burners are separate from each other, and consequently the parts above described as 10 comprising the burner will be duplicated.

It will be obvious to those skilled in the art that the details of construction herein illustrated may be varied without in any way departing from the spirit of my invention, 15 and I therefore reserve the right to make any and all such changes as come within the spirit of the appended claims.

Having fully described my invention, what I claim as new, and desire to secure by Letters 20 Patent, is—

1. In a steam-generator, a series of boilers, a feed-water pipe and a steam-drum communicating with all the boilers, and an automatic valve at both the steam-outlet and wa- 25 ter-inlet of each boiler, the valve at the steam-outlet of each boiler being normally closed.

2. In a steam-generator, a series of boilers, a perforated pipe extending through each boiler, a steam-drum connected to one end of 30 each of said pipes, a feed-water pipe connected to the other end of each of said pipes, and an automatic valve at the steam-outlet and also at the steam-inlet of each boiler.

3. In a steam-generator, a series of boilers, a perforated pipe extending vertically 35 through each boiler, means for connecting said perforated pipes both above and below the boilers, and check-valves at each end of each of said pipes, whereby when the pressure in any one boiler suddenly falls below that in the other boilers, the check-valves close and cut off communication between said boiler and the remaining boilers.

4. In a steam-generator, a series of boilers 45 having communication with each other both above and below the water-line, and valves to automatically close the communication between any one boiler and the remaining boilers when the pressure in any one boiler is suddenly reduced, the valves which are situated above the water-line being normally closed.

5. In apparatus of the class described, a plate, and a series of boilers secured thereto, 55 said plate forming the top of the boilers, said boilers having communication with each other both above and below the water-line.

6. In apparatus of the class described, a plate, a series of boilers secured thereto, said 60 plate forming the top of the boilers and said boilers having normally open communication with each other both above and below the water-line, and means to automatically close the communication between any one boiler and the remaining boilers when the pressure in said boiler is suddenly reduced.

7. In a steam-generator, a plate, a series of

boilers connected thereto, said plate forming the top of the boilers, a perforated pipe connected to the bottom of each boiler and extended through the plate, a steam-pipe connecting the upper ends of said perforated pipes, and means for connecting the lower ends thereof, whereby the same water-level is automatically maintained in all the boilers. 75

8. In a steam-generator, a plate, a series of boilers connected thereto, said plate forming the top of the boilers, a perforated pipe connected to the bottom of each boiler and extended through the plate, a steam-pipe connecting the upper ends of said perforated pipes, means for connecting the lower ends thereof, and check-valves at the upper and lower ends of said perforated pipes, whereby when the pressure in any one boiler suddenly falls below that in the others, the check-valves close communication between said boiler and the remaining boilers. 80

9. In a steam-generator, a plate, a series of boilers secured to the plate, the plate forming the end of the boilers, flues extending through the boilers and supported at one end by the boiler, and at the other end by the plate, and a combustion-chamber underneath all the boilers of the series. 90

10. In a steam-generator, a plate, a series of boilers, each comprising a cup-shaped boiler-shell secured to the plate, the said plate forming the end of the boilers, flues extending through the boiler-shells, said flues being supported at one end in the bottom of the shells and at the other end in the said plate, a combustion-chamber underneath all the boilers of the series, said boilers being connected both above and below the water-line. 100

11. In a steam-generator, a casing, a partition extending across the same and forming two chambers, one of said chambers being a combustion-chamber, a series of boilers secured to the under side of said partition and inclosed in the combustion-chamber, the flues in the boilers opening into the other chamber. 110

12. In a steam-generator, a casing, a partition dividing the same into a combustion-chamber and a smoke-chamber, a series of boilers secured to one side of the partition and inclosed in the combustion-chamber, a steam pipe or drum in the smoke-chamber, and connected to each boiler, and a communication between said boilers below the water-line. 120

13. In an apparatus of the class described, a plate and a series of boilers secured thereto, said boilers having communication with each other both above and below the water-line. 130

14. In an apparatus of the class described, a plate, a series of boilers secured thereto, said boilers having communication with each other both above and below the water-line, and means to automatically close the communication between any one boiler and the remaining boilers when the pressure in said boiler is suddenly reduced. 140

15. In a steam-generator, a casing, a plate or partition extending across the same and forming two chambers, one of which constitutes a combustion-chamber, a series of boilers secured to the under side of said plate and inclosed in the combustion-chamber, and means to automatically cut out any one boiler of the series in case of accident thereto.
16. In a steam-generator, a casing, a partition extending across the same and forming two chambers, one of which constitutes a combustion-chamber, a plurality of connected boilers secured to the under side of said partition and situated within the combustion-chamber.
17. In a steam-generator, a casing, a partition extending across the same and forming two chambers, one of which constitutes a combustion-chamber, a plurality of connected boilers secured to the under side of said partition and situated within the combustion-chamber, and means to cut out any one boiler of the series in case of accident thereto.
18. A casing having a plate or partition extending across the same, a burner supported by the casing at its bottom, the chamber formed between the burner and partition constituting a combustion-chamber, and a boiler

supported by the partition, said boiler being separate from the casing and situated within 30 the combustion-chamber.

19. In a steam-generator, a casing having a partition dividing it into a smoke-chamber and a combustion-chamber, a burner supported by the casing and forming the bottom 35 of the combustion-chamber, and a boiler situated within the combustion-chamber and secured to the partition said boiler being separate from the casing.

20. In a steam-generator, a casing having 40 a partition dividing it into a smoke-chamber and a combustion-chamber, a burner supported by the casing and forming the bottom of the combustion-chamber, and a plurality of connected boilers situated within the combustion-chamber and each secured to the partition, the flues of each boiler leading through 45 the latter and also through the partition.

In testimony whereof I have signed my name to this specification in the presence of 50 two subscribing witnesses.

CHARLES CROMPTON.
